UNITED STATES PATENT OFFICE.

GEORGE LYMAN BURDETT, OF KEENE, NEW HAMPSHIRE.

CHAIR.

SPECIFICATION forming part of Letters Patent No. 317,497, dated May 12, 1885.

Application filed February 4, 1884. (No model.)

To all whom it may concern:

Be it known that I, GEORGE LYMAN BURDETT, of Keene, in the county of Cheshire, of the Commonwealth of New Hampshire, have invented a new and useful Improvement in Chairs; and I do hereby declare the same to be described in the following specification and represented in the accompanying drawings, of which—

10 Figure 1 is a top view, and Fig. 2 a median section, of a chair of my improved kind. Fig. 3 is a top view of the seat as provided with tenons for securing it to the posts of the chair-frame.

15 The nature of my improvement is defined in the claim hereinafter presented.

In constructing the chair I make the seat in part of a suitable frame, *a*, having tenons *b* extending from it at its four corners, such 20 tenons being to enter corresponding notches formed in the four posts *d* of the chair-frame. The said frame *a* I cover with a binding of wood or other proper material, wound or carried around it from front to rear and side to 25 side of it, the lengthwise coils being interwoven with the widthwise one, in a manner substantially as shown in Fig. 3.

Directly in front of the front edge of the seat I extend from one of the front posts to the other

of the frame and secure to them a rung, *e*, 30 which not only serves to strengthen the chair-frame, but as a protection of the front edge or portion of the seat-covering from injury or wear.

I am aware that a slatted-seated chair has been devised which is provided at the front 35 of the seat with a binding strip, to which the slatted part of the seat is secured, and which strip is a portion of the seat structure. I place the rung *e* in front of and separate from the seat. This rung thus protects the looped portions of the wood binding where it covers the front of the seat-frame, and thus keeps this binding from being worn and broken. The rung *e*, being distinct from the seat, can be renewed without affecting the seat structure. 45

What I claim is—

In a chair such as described, the chair-frame, in combination with the seat, consisting of the frame *b* and the wood binding *a*, wound about the frame, and the rung *e*, 50 secured in front of the seat, whereby the front of the wood binding is kept from wear, as set forth.

GEORGE LYMAN BURDETT.
